COMBINED TWIN SOFA BED AND TABLE UNIT

John Maguire, Los Angeles, Calif., assignor, by mesne assignments, to Duo-Bed Corporation, Los Angeles, Calif., a corporation of Delaware

Filed Aug. 8, 1960, Ser. No. 61,664

Term of patent 14 years

(Cl. D5—4)

FIG. 1.

FIG. 2.

FIG. 3.

FIG. 1 is a perspective view showing a combined twin sofa bed and table unit showing my new design in closed position;

FIG. 2 is a top plan view of the same;

FIG. 3 is a perspective view of the same in open position with one bolster removed.

The dominant features of my design are shown in full lines, the back of the combined twin sofa bed and table unit being conventional; and the characteristic feature of my design resides in the table, namely in its oblong configuration and in the narrow vertically extending, full length, contrasting side panel on the front of the table, all as shown.

I claim:

The ornamental design for a combined twin sofa bed and table unit, substantially as shown and described.
